UNITED STATES PATENT OFFICE

2,372,118

COATING APPARATUS

Thomas J. Radcliffe, Belleville, N. J., assignor to
 General Electric Company, a corporation of
 New York

Application April 23, 1943, Serial No. 484,219

10 Claims.

(Cl. 91—18)

My invention relates, in general, to apparatus for applying coatings to electrically conductive strip and similar material. More particularly, my invention relates to apparatus for applying a coating of glow-preventing material to selected portions of a metal strip from which glow lamp electrodes are to be later punched. The present application is a continuation-in-part of my prior United States application Serial No. 449,027, filed June 29, 1942.

Glow discharge lamps comprising closely spaced electrodes mounted within a sealed envelope are well-known in the art. A species of such lamps comprising two spaced, juxtaposed electrodes shaped as quadrants of a hollow sphere and so arranged as to jointly present a hemispherical surface is disclosed in United States Patent No. 1,965,586, issued July 10, 1934 to T. E. Foulke. This patent also discloses the use of aluminum or aluminum oxide, among other materials, for excluding the glow discharge from the inner surface of the electrodes and confining said discharge to the outer hemispherical surface thereof. Heretofore the aluminum or aluminum oxide, hereinafter called anti-glow material, has been painted on the inner surface of the electrodes by hand with a small brush. This is a slow, expensive method not suitable for mass production, and one in which complete and uniform coverage of the desired surface is not always obtained.

The prior application mentioned hereinabove relates to the method of manufacturing such electrodes or cathodes while the present application relates to apparatus for applying the anti-glow material to a given portion of the metal strip out of which the electrodes are to be shaped or punched.

One object of my invention is to provide apparatus for applying a coating to a given surface area of electrically conductive strip material or the like.

Another object of my invention is to provide apparatus for applying a coating of anti-glow material to a given surface area of a metal strip out of which a plurality of electrodes may be fabricated, as by punching.

A feature of the invention is the provision of means for heat treating the applied coating material and its metal support by the passage of an electric current through the coated metal support whereby an adherent baked-on coating of said material is produced on the metal support without impairing the ductility of the metal support

for subsequent fabrication or punching into electrodes.

Further objects and advantages of my invention will appear from the following description of 5 a species thereof and from the accompanying drawings, in which:

Fig. 1 is a front elevation of a coating machine comprising my invention; Fig. 2 is a section on the line 2—2 of Fig. 1; Fig. 3 is a forward end view of the guiding and feed means of the apparatus comprising my invention as viewed from the line 3—3 of Fig. 1; Fig. 4 is a longitudinal vertical section through the coating applicator means and associated parts, the section being 10 taken on the line 4—4 of Fig. 3; Fig. 5 is a top view, partly in section, taken along the line 5—5 of Fig. 4; Fig. 6 is a vertical section taken on the line 6—6 of Fig. 1; and Fig. 7 is a diagrammatic wiring diagram showing the arrangement for 15 passing electrical current through the coated metal strip.

Referring to the drawings, the machine there 20 shown comprises vertically spaced supply and collector reel holders 10, 11, respectively, rotatably mounted on an upstanding support bracket 12 rigidly secured to an inverted channel iron 13 bolted to the table portion 14 of a stationary stand or bed member 15. The two reel holders 10 and 11 each comprise a pair of flanges or discs 25 16, 17 between which supply and take-up reels or spools 18, 19, respectively, are held. The supply reel 18 on the lower or supply reel holder 10 is provided with a coil 20 of the metal strip material 21 to be processed or coated, and the said metal strip 21 is drawn or pulled through the various parts of the machine and then wound up on 30 the take-up or collector reel 19.

As shown in Fig. 2, the two flanges 16, 17 of 35 each reel holder 10, 11 are mounted on vertically-spaced horizontal shafts 22, 23, respectively, which are journaled in bearings 24 on the support bracket 12. The flange 16 of each reel holder 10, 11 is threaded onto its respective support shaft 22 or 23 and is locked in position against rotation 40 thereon by a nut 25 threaded on the said shaft and screwed up tight against the flange. Each of the threaded flanges 16 is provided with a small concentric boss or centering hub 26 on its inner side for centering the reels or spools 18, 19 45 in the reel holders 10, 11. The other flange 17 of each reel holder 10, 11 is slidably mounted on its respective support shaft 22 or 23, the flange 17 of the lower or supply reel holder 10 being held in position on the shaft 22 by a retaining nut 27 50 threaded on the shaft 22 and locked against rotation.

tation by a second or locking nut 28 threaded on the said shaft and screwed up tight against the retaining nut 27. The said flange 17 of the supply reel holder 10 is so positioned on the shaft 22 as to hold the supply reel 18 loosely between the two flanges 16, 17 so as to permit free rotation of the said reel on the reel holder 10. The flange 17 of the upper or collector reel holder 11 is continuously urged against the collector reel 19 thereon by a compression coil spring 29 fitting over the shaft 23 outwardly of the flange 17 and compressed between the said flange and a retaining nut 30 threaded on the shaft 23. The said retaining nut 30 is locked against rotation or unloosening by a second or locking nut 31 threaded on the shaft 23.

The collector reel holder 11 and the collector reel 19 mounted thereon are rotated in a clockwise direction, as viewed from the front of the machine (Fig. 1), by suitable means, as by an electric motor 32 connected through a speed reducer 33 to the shaft 23 of the collector reel holder 11. The electric motor 32 and speed reducer 33 are fixedly mounted on the machine stand or base 15 below the table 14 thereof and are interconnected by a belt 34 and pulleys 35, 36 on the motor and speed reducer shafts 37, 38, respectively. The shaft 23 of the collector reel holder 11 is driven by the speed reducer 33 through suitable drive means, such as by a roller chain 39 and sprockets 40, 41 on the rear ends of the speed reducer and reel holder shafts 38 and 23, respectively. Inasmuch as the take-up reel 19 is clamped between the two flanges 16, 17 of the take-up reel holder 11 merely by spring pressure (i. e., the pressure exerted by spring 29), the said reel 19 will therefore slip relative to the driving flange 16 of the reel holder 11 whenever any drag is placed on the take-up reel. Thus, the combination of the fixed or driving flange 16 and the spring-pressed flange 17 of the take-up reel holder 11 may be considered as forming a friction or slipping clutch for driving the take-up reel 19.

As shown in Fig. 1, the metal strip 21 is continuously unwound from the supply reel 18 by a pair of motor-driven feed rollers 42, 43 which feed the metal strip to a coating applicator device 44 comprising a coating pot or tank 45 mounted on the channel 13 and containing a bath 46 of the coating material (such as aluminum paint) to be applied to the metal strip. As the metal strip 21 is unwound from the supply reel 18 by the feed rollers 42, 43, it is first drawn under a guide roller 47 rotatably mounted on an upstanding U-shaped support bracket 48 fastened to the channel 13, the guide roller 47 being mounted between the upstanding arms of the said bracket.

From the guide roller 47, the metal strip 21 is then drawn in a substantially horizontal direction by the feed rollers 42, 43 through lateral guiding means in the form of a pair of laterally spaced guide plates or fingers 49, 49 (Fig. 3) between which the metal strip passes. The said guide fingers 49, 49 extend at right angles to the metal strip and have their inner, opposed ends notched, as indicated at 50, to provide a guideway for the metal strip. The guide fingers 49 are adjustably mounted on a support bracket 51 fastened to the coating pot 45, the said bracket 51 being provided with a pair of laterally spaced arms 52, 52 to which the guide fingers are fastened each by a pair of laterally spaced screws 53. To permit lateral adjustment of the guide fingers 49 so as to accommodate metal strip of different

widths, the said fingers are each provided with a horizontally elongated slot 54 through which the fastening screws 53 extend.

After passing between the guide fingers 49, the metal strip 21 next passes between the rotating feed rollers 42, 43 which are rotatably mounted on the support bracket 51 between the arms 52 thereof. The said feed rollers 42, 43 are preferably made of rubber and are provided with shafts 55, 56, respectively, which are journaled in bearings 57 in the support bracket arms 52. The feed rollers are driven by the speed reducer 33 through suitable drive means, such as by a roller chain 58 and sprockets 59, 60 on the speed reducer shaft 38 and the upper feed roller shaft 55, respectively. The lower feed roller 43 is rotated in a direction opposite to that of the upper feed roller 42 by means of similar intermeshing spur gears 61, 62 on the feed roller shafts 55, 56, respectively.

Following its passage through the feed rollers 42, 43, the metal strip 21 is next drawn under a front guide roller 63, thence over a coating applicator roller 64 which runs in the bath 46 of coating material, and then under a rear guide roller 65. The front and rear guide rollers 63, 65 are rotatably mounted on horizontal pins or shafts 66 supported in ears 67, 67' on the coating pot 45 and are formed with annular grooves or channels 68 (Fig. 5) corresponding in width to the width of the metal strip 21 so that the said strip is received therein as it passes under the guide rollers 63, 65. The grooves 68 in the said guide rollers thus serve as guideways for laterally centering and directing the metal strip 21 over the applicator roller 64. To permit the interchange of the guide rollers 63, 65 with other guide rollers having guide channels or grooves 68 of different widths for the accommodation and proper guiding of metal strip of different widths, the roller support pins 66 are removably mounted in place in the support ears 67, 67', as by set screws 69 for instance.

The applicator roller 64, which may be made of steel or which may have a steel surface, is rotatably mounted on a pin or shaft 70 having a head 71 at one end thereof and journaled in bearings 72 in the coating pot 45. The said roller 64 is formed with a flat edge or face 73 narrower than the width of the metal strip 21 so that it applies an even coating of the coating material or aluminum paint 46 along the center portion of one side only (the underside) of the said strip as the strip is drawn over the applicator roller 64.

To permit the interchange of the applicator roller 64 with other rollers having faces 73 of different widths, for use with metal strip material 21 of different widths, the roller support pin 70 is removably held in place in its bearings 72 by a small leaf or plate spring 74 pivotally fastened at one end to the coating pot 45, as by a screw 75, and bearing at its other end against the headed end 71 of the pin 70. The end thrust exerted by the said spring 74 against the pin 70 holds the head 71 of the pin against the outer side of the coating pot 45, thus locking the pin in place in its bearings 72. By moving the spring 74 about its pivot point so as to clear the end of the pin 70, the said pin can then be slid out of its bearings 72 and a different sized applicator roller 64 substituted for the one theretofore in use.

The metal strip 21 is continuously pressed down 75 against the applicator roller 64 by a pressure

roller 76 so that minor deviations in the flatness of the strip do not result in uneven coating thereof. The said pressure roller 76 is preferably made of soft rubber and is rotatably mounted on a weighted lever or arm 77 pivoted on a pin 78 which is supported on the arms 52 of the feed roller support bracket 51. The free end of the said lever 77 is provided with a depending U-shaped bracket 79 which supports a pin or shaft 80 on which the pressure roller 76 is rotatably mounted. A weight 81, fastened to the lever 77 (as by bolt 82) at a point adjacent the free end thereof, insures the exertion of sufficient pressure on the metal strip by the pressure roller 76 to cause the applicator roller 64 to rotate as the strip passes over it, thus bringing up a constant supply of the coating material from the bath 46 for application to the continuously moving strip.

The face 73 of the applicator roller 64 is made slightly narrower than the strip 21 to be coated so as to leave a narrow uncoated portion at each side of the strip, thus avoiding any possibility of the applied coating material 83 creeping or flowing over the edges of the strip onto the other side thereof. To insure the application of the coating material 46 to the strip 21 only up to the width of the roller face 73 and in an even amount, the excess coating material carried up by the applicator roller 64 is removed from the face 73 and sides 84 thereof by a wiper plate or blade 85 pivoted at one end on a pin 86 supported on the coating pot ears 67 and resting at its other end on the face 73 of the applicator roller. The free end of the said wiper plate 85 is provided with a U-shaped notch 87 just wide enough to permit the roller 64 to rotate therethrough so that the arms 87, formed by the said notch, scrape all the excess coating material from the sides 84 of the applicator roller.

Following the application of the coating 83 to the metal strip 21, the said strip is then heated by passing an electrical current through it in order to bake the coating material thoroughly. This electrical heating of the metal strip 21 is accomplished, according to the invention, by drawing the coated strip tightly, coated side out, over a series of three vertically-spaced stationary contact drums 88, 89 and 90 whereby the uncoated side of the metal strip makes electrical contact with the said drums. The contact drums 88, 89 and 90 are mounted on, and insulated from, an upstanding support bracket or channel iron 91 fastened to the channel iron 13 on the table 14. As shown in Fig. 6, each of the said contacts 88, 89 and 90 are secured to the channel 91 by a bolt 92 and are insulated from the channel by a flanged bushing 93 and a washer 94 both of suitable insulating material, preferably a plastic such as that commercially known as "Transite." To prevent the metal strip 21 from sliding or creeping off the contact drums 88, 89 and 90, each of the said drums is provided with out-turned annular flanges 95 at each side thereof which serve to guide and hold the metal strip in place on the said drums.

The electrical contacts 88, 89 and 90 are connected to a suitable source of electrical energy capable of passing sufficient energy through the ever-changing portion of the strip 21 bridging said contacts to raise it to the baking temperature of the coating material 83. For this purpose, the first and last contacts 88 and 90, respectively, may be connected to the opposite terminals of the secondary 96 of a step-down transformer 97

mounted on the stand 15 while the intermediate or second contact 89 is connected to the midpoint of the secondary 96, as indicated in Fig. 7. The primary 98 of the transformer 97 is connected across the terminals of a suitable source of alternating current, such as a 220-volt, 60 cycle current source. I have found that a current of about 50 amperes through the ever-changing coated portion of the metal strip 21 bridging the contacts is effective for heating the said portion sufficiently to produce an adherent, uniform baked-on coating of aluminum paint on a nickel strip having a width of approximately $\frac{5}{8}$ inch and a thickness of approximately 0.010 inch when the speed of movement of the strip 21 over the contacts 88, 89 and 90 is such that a given point thereon is heated for approximately 5 seconds. A transformer 97 capable of changing a 220-volt current supply of commercial (60-cycle) frequency to 2.5 volts between the midpoint and the opposite ends of the secondary 96 is suitable for the above purpose.

While the center contact 89 and its connection to the transformer secondary may be omitted, I have found that it minimizes sparking at the end contacts 88 and 90 and is therefore desirable. Furthermore, the said center contact 89 avoids overheating portions and underheating other portions of the metal strip 21 at the beginning and at the end of a run. At such times, the machine is stopped and current passed through that portion of the strip which would not otherwise be sufficiently or properly heated. The center contact 89 avoids such undesired temperature distribution and thus eliminates spoilage of material.

After passing over the last contact drum 90, the metal strip 21 is then drawn over a flanged sheave or idler pulley 99 rotatably mounted on a stud 100 extending from the support channel 91. The said sheave guides the coated strip 21 from the last contact 90 to the take-up or collecting reel 19 onto which the strip is then wound.

The drive connections for the feed rollers 42, 43 and the collector reel 19 are so arranged that the motor 32, acting through the friction clutch formed by the stationary flange 16 and the spring-pressed flange 17 of the collector reel holder 11, tends to rotate the collector reel 19 at a higher rate of speed than that of the feed rollers 42, 43 and to thus pull the metal strip 21 through the apparatus at a higher speed than the feed rollers will allow. Sufficient tension is therefore exerted on the loop-like portion of the strip 21 between the feed rollers 42, 43 and the collector reel 19 to hold the said strip portion taut and firmly against the electrical contacts 88, 89 and 90 so as to avoid excessive sparking between the strip and the said contacts.

The strip 21 is continuously passed over and between the contacts 88, 89 and 90 at a rate such that the coating material 83 is thoroughly baked thereon without impairing the ductility of the strip for subsequent fabrication or shaping into articles such as the glow lamp electrodes referred to hereinbefore. This rate may be determined by trial runs of the apparatus.

Undue heating of the electrical contacts 88, 89 and 90, particularly the last contact 90, by the hot portion of the strip 21 passing over its surface may be prevented by providing sufficient heat dissipating capacity for the contacts. If the heat dissipating area of the contact itself is not sufficient for this purpose, then heat radiating

fins on the contacts or liquid cooling means may be used.

Where the coated strip 21 is to be fabricated into electrodes for glow lamps, I have found that the aluminum paint sold by the Sahlin Chemical and Color Company of Camden, New Jersey, under the designation of No. 2056 Aluminum, is eminently satisfactory for use as the coating 83 of anti-glow material.

What I claim as new and desire to secure by Letters Patent of the United States is:

1. Apparatus for coating a metal strip with a bakable material comprising in combination, applicator means for applying the coating material to one side only of said strip, electrical means comprising spaced contacts for engaging with the uncoated side of said strip and for passing electrical energy through said strip to heat it sufficiently to bake the coating thereon, and means for moving said strip successively into effective relation to said applicator means and over said contacts.

2. Apparatus for coating a metal strip with a bakable material comprising in combination, applicator means for applying the coating material to one side only of said strip, electrical means comprising spaced contacts for engaging with the uncoated side of said strip and for passing electrical energy through said strip to heat it sufficiently to bake the coating thereon, means for moving said strip successively into effective relation to said applicator means and over said contacts, and adjustable guide means for laterally aligning said strip with said applicator means, said guide means providing a guide opening of preselectable width to accommodate strip material of different widths.

3. Apparatus for coating a metal strip with a layer of bakable coating material comprising an applicator roller for continuously applying the coating material to one side only of the strip, electrical means comprising spaced contacts for engaging with the uncoated side of said strip and for passing electrical energy through said strip to heat it sufficiently to bake the coating material thereon, and means for continuously moving said strip over said applicator roller and thence over said contacts.

4. Apparatus for coating a metal strip with a layer of bakable coating material comprising applicator means for continuously applying the coating material to a restricted mid-portion of one side only of the strip, electrical means comprising spaced contacts for engaging with the uncoated side of the coated strip and for passing electrical energy through said strip to heat it sufficiently to bake the coating material thereon, and means for continuously moving said strip into effective coating relation to said applicator means and thence over said contacts, said last-named means exerting sufficient tension on said strip to draw it taut and hold it firmly against the said contacts.

5. Apparatus for coating a metal strip with a layer of bakable coating material comprising applicator means for continuously applying the coating material to one side only of the strip, a plurality of spaced contacts for engaging with the uncoated side of the coated strip, a transformer having a secondary connected to said contacts to pass an electrical current through those portions of the metal strip which bridge the said contacts at a given instant, and means for continuously moving said strip into effective

coating relation to said applicator means and thence over said contacts.

6. Apparatus for coating a metal strip with a layer of bakable coating material comprising applicator means for continuously applying the coating material to one side only of the strip, a set of three spaced contacts for successively engaging with the uncoated side of the coated strip, a transformer having a secondary the opposite ends of which are connected to the first and third ones of said contacts and an intermediate point of which is connected to the intermediate one of said contacts, and means for continuously moving said strip into effective coating relation to said applicator means and thence over said contacts.

7. Apparatus for coating a metal strip with a layer of bakable coating material comprising supply and collector reel holders for rotatably supporting supply and collector reels, roller-applicator means for continuously applying the coating material to one side only of the strip, feed-roller means for continuously drawing the metal strip off the supply reel and feeding it to said roller-applicator means, a plurality of spaced contacts for engaging with the uncoated side of the coated strip, a source of current supply connected to said contacts for passing electrical energy through those portions of the metal strip which bridge the said contacts at a given instant to heat the said strip portions sufficiently to bake the coating material thereon, and means including a slipping clutch for rotating said collector reel at a speed tending to collect the metal strip faster than it is fed to the roller-applicator means by said feed-roller means whereby sufficient tension is exerted on the coated portion of the strip to draw it taut and hold it firmly against the said contacts.

8. Apparatus for coating a metal strip with a layer of bakable coating material comprising supply and collector reel holders for rotatably supporting supply and collector reels, a coating pot containing a bath of the coating material to be applied to the strip, an applicator roller rotatably mounted on said coating pot to run in said bath of coating material, said applicator roller having an applicating surface of a width less than the width of said strip, feed-roller means for continuously drawing the strip off the supply reel and feeding it over said applicator roller, guide means for laterally aligning said strip with respect to said applicator roller, a pressure roller for pressing said strip into firm contact with said applicator roller, a wiper plate resting on and straddling said applicator roller for removing excess coating material from the applicating surface and side walls of the applicator roller prior to the engagement of said applicating surface with said strip, a plurality of spaced contacts for engaging with the uncoated side of the coated strip, a source of current supply connected to said contacts for passing electrical energy through those portions of the metal strip which bridge the said contacts at a given instant to heat the said strip portions sufficiently to bake the coating material thereon, and means including a slipping clutch for rotating said collector reel at a speed tending to collect the metal strip faster than it is fed to the said applicator roller by said feed-roller means whereby sufficient tension is exerted on the coated portion of the strip to draw it taut and hold it firmly against the said contacts.

9. Apparatus for coating a metal strip with a

bakable material comprising in combination, applicator means for applying the coating material to the underside only of the strip while the latter is continuously advanced past said applicator means in a transversely level position, and electrical means comprising spaced contacts for engagement with the uncoated side only of the advancing strip to thereby pass an electric current through said strip to heat it sufficiently to bake the coating thereon.

10. Apparatus for coating a metal strip with a bakable material comprising in combination, applicator means for applying the coating material

to the strip while the latter is continuously advanced past said applicator means in a transversely level position, said applicator means applying the coating material to the underside only of the advancing strip in the form of a band therealong of less width than and spaced from the side edges of the strip, and electrical means comprising spaced contacts for engagement with the uncoated side only of the advancing strip to thereby pass an electric current through said strip to heat it sufficiently to bake the coating thereon.

THOMAS J. RADCLIFFE.
